(57) **CLAIM**

The ornamental design for a vehicle tire, as shown and described.

DESCRIPTION

FIG. 1 is a left side view of a vehicle tire showing my new design;

FIG. 2 is a front side view thereof;

FIG. 3 is a rear view thereof;

FIG. 4 is a top view thereof; and,

FIG. 5 is a partial enlarged view of FIG. 2.

The bottom view is the same as the front view. The right side view is the same as the left side view.
